UNITED STATES PATENT OFFICE.

CARL MAGNUS ANDERSON, OF BATAVIA, ILLINOIS.

MOLD FOR CURING AND FORMING BLOW-OUT PATCHES.

1,372,215.

Specification of Letters Patent. Patented Mar. 22, 1921.

Application filed July 28, 1920. Serial No. 399,550.

To all whom it may concern:

Be it known, that I, CARL M. ANDERSON, a citizen of the United States, residing at Batavia, in the county of Kane and State of Illinois, have invented a new and useful 5 Mold for Curing and Forming Blow-Out Patches, of which the following is a specification.

It is the object of this invention to provide 10 a simple but efficient means whereby blowout patches may be cured and formed.

Within the scope of what is claimed, a 15 mechanic may make changes without departing from the spirit of the invention.

15 In the drawings:—

Figure 1 shows in side elevation, a device 20 constructed in accordance with the invention, parts being broken away; and Fig. 2 is an end elevation wherein parts are broken away.

The device forming the subject matter 25 of this application preferably is made of metal and includes a hollow box-like base or main member 1 provided on its bottom with ribs 2 adapted to coöperate with a supporting frame (not shown). A steam supply pipe 3 communicates with the interior of the main member 1 and may be mounted in the bottom of the member 1, 30 or in some other part thereof. The top of the main member 1 is curved both longitudinally and transversely to correspond to the ordinary curvatures of a vehicle tire.

The numeral 5 denotes an auxiliary member 35 which may be hollow, if desired. The auxiliary member, on its lower and side surfaces, is curved longitudinally and transversely to fit in the upper portion of the main member 1.

40 The numeral 6 denotes a yoke provided in its intermediate portion with bosses 7 connecting a reinforcing web 8, the web being connected with the end portions of the yoke. One end of the yoke is united by a pivot 45 element 9 with one end of the main member 1. The other end of the yoke 6 is connected by a pivot member 10 with the other end of the main member 1. The pivot member may be constructed in any desired way, but it 50 exercises a double function, in that it serves as a pivotal mounting for one end of the yoke 6 and constitutes, also an outlet valve for the hollow box-like member 1. With this end in view, the pivot member 10 may 55 be supplied with a longitudinal passage 11 communicating with the interior of the

main member 1, and with a side port 12. A valve 14 is threaded into the outer end of the pivot member 10 and may be seated to prevent an outflow through the passage 11 60 and the port 12. Screws 15 are threaded into the intermediate portion of the yoke 6, and through the bosses 7, the screws being adapted to exert a pressure on the auxiliary member 5.

The numeral 16 denotes a U-shaped flap grip, including a resilient arch 17 carrying plates 18 at its ends.

In practical operation, the material which 70 it is to be formed into a blowout patch is seated in the top of the box-like member 1. The auxiliary member 5 is inserted into the concavity of the patch and the screws 15 are advanced to press the auxiliary member 5 on the patch. The longitudinal edges of 75 the patch 19, which constitutes flaps 20, are folded downwardly on the outer sides of the box-like main member 1. The flap grip 16 is then placed astride of the yoke 6, the plates 18 pressing the flaps 20 of the patch 80 19 against the side walls of the main member 1, since the arched portion 17 of the flap grip is somewhat resilient.

By moving the valve 14 to an open position, air may be permitted to escape from 85 the interior of the main member 1, steam being supplied through the pipe 3.

Having thus described the invention, what is claimed is:—

1. In a device of the class described a 90 main member; an auxiliary member coöperating with the main member; and a flap grip located between the ends of the auxiliary member and spanning the auxiliary member transversely, the grip comprising 95 a resilient arch and parts coöperating with the sides of the main member, said parts being held in coöperating relation with respect to the sides of the main member by the resiliency of the arch.

2. In a device of the class described, a 100 main member; an auxiliary member coöperating therewith; a yoke pivoted to the main member; a compression element carried by the yoke and coacting with the auxiliary 105 member; and a flap grip spanning the yoke and the auxiliary member and comprising parts coöperating with the sides of the main member.

3. In a device of the class described, a 110 hollow main member; an auxiliary member coöperating with the main member; a yoke;

compression means carried by the yoke and engaging the auxiliary member; and pivot elements uniting the yoke with the main member, one pivot element having a passage 5 communicating with the interior of the main member; and a valve mounted in the pivot element and controlling the passage.

In testimony that I claim the foregoing as my own, I have hereto affixed my signature in the presence of two witnesses.

CARL MAGNUS ANDERSON.
